WINDOW CONSTRUCTION

Waldo L. Kraemer, Brooklyn, N. Y., assignor to
Kearfott Engineering Company, Inc., a corpora-
tion of New York

Application May 7, 1934, Serial No. 724,320

5 Claims. (Cl. 114—177)

The invention herein disclosed relates to a window construction especially suitable for ships, and in particular to a weathertight window construction in which the window-pane is readily removable.

Commonly, windows of this type include a frame having an opening therethrough, a window-pane movable in a plane parallel to the frame, window-pane guideways for guiding a window-pane in movement between open and closed positions thereof, and traversing mechanism for moving the window-pane. In certain constructions the window-pane is movable laterally of the frame for pressing the window-pane, in the closed position thereof, firmly against a gasket mounted on the frame around the opening therethrough. When the window-pane is thus pressed against the gasket there is a weather-tight closure of the window opening through the frame. For certain ships it is desirable to have a window construction such that the window-pane may be readily and easily removable. This is particularly important on battleships as the window-panes, when mounted in the window, are frequently broken during target practice, and it is an object of this invention to provide a window construction adapted for this purpose.

In accordance with the invention, a window construction of the type referred to includes guideways for the window-pane which are secured to the frame and embrace the side edges of the window-pane. Each such guideway comprises a section which is readily removable to release the window-pane from the guideway. The window-pane is also readily and easily disconnected from the window-pane traversing mechanism. For example, in one form of window constructed in accordance with this invention, two side, window-pane guideways, which are slidably mounted on the window frame for lateral movement with respect thereto, embrace the side edges of the window-pane. Each guideway includes a removable section adjacent the window opening through the frame, which may be removed to free the window-pane. Embracing each removable section of the guideways there is a bracket which is mounted on the frame and which carries mechanism for moving the guideways laterally to the frame. The window-pane traversing mechanism includes a carriage moved by the traversing mechanism and a clamp embracing an end edge of the window-pane is releasably connected to the carriage.

Such a window construction is illustrated in the accompanying drawings in which

Fig. 1 is an elevation of the window;

Fig. 2 is a sectional, end elevation taken along the irregular line 2—2 of Fig. 1;

Fig. 3 is a fragmentary, sectional plan taken along the line 3—3 of Fig. 1; and

Fig. 4 is a fragmentary, sectional elevation taken along the line 4—4 of Fig. 3.

The window illustrated includes a frame 1 having an opening therethrough constituting the window opening which is defined by inboard and outboard lateral flanges 1a and 1b. The frame is secured in a vertical position to the plating of the vessel with the outboard flange 1b extending through the plating. Brackets 1c and 1d on opposite sides of the frame, below the window opening, extend laterally of the frame and support a cross bar 2 which supports the window-pane traversing mechanism.

The window-pane traversing mechanism is mounted in a bracket 3 secured to the cross bar 2 and includes a vertical, threaded shaft 4 journaled in the bracket at its upper end and at its lower end in a bar 5 extending between two angle irons 6 and 7 secured to and extending downwardly from the bracket 3. On the upper end of the shaft 4, there is mounted on the shaft a gear 8 for rotation with the shaft. The gear 8 meshes with a gear 9 mounted on a stub shaft 10 having one end squared and extending through the cross bar 2. Fitted on the squared, protruding end of the stub shaft 10, there is a handle 11 by means of which the shaft 4 may be manually rotated. When rotated, the shaft 4 effects vertical movement of a nut 12 threaded on the shaft and restrained against rotation therewith by its connection to a carriage 13. The nut 12 has a pair of spaced lugs 12a, 12b, and 12c, 12d on diametrically opposite sides thereof. Between each pair of lugs there extends a lateral arm of a bifurcated extension 13a of the carriage 13. The carriage 13 is provided with a pair of slots into which extend tongues 14a and 14b of a clamp 14 which clamps the lower edge of the window-pane 15, a soft material 16 being between the window-pane and the metal clamp. The tongues 14a and 14b are held in the slots in the carriage 13 by thumb screws 17 and 18, which extend through transverse openings in the carriage and are threaded into the tongues.

The window-pane and the carriage 13 move vertically in vertical, channel-shaped guideways 19 and 20 mounted on each side of the frame and which embrace the side edges of the window-pane. Each vertical guideway includes two sections, an upper section a and a lower section b. The upper section 19a of the guideway 19 has a bracket 19c thereon which is slidably mounted on a stud 21 threaded into a lug 22 on the upper end of the frame 1. The section 20a of the guideway 20 is similarly mounted on a stud 23. The lower section 19b of the guideway 19 is supported at its upper end on three round pins 24, 25 and 26 extending perpendicularly from the surface of the web of the guideway. These pins extend into slots in the bracket 1c on the frame 1 and pro-

vide a mounting which permits limited lateral and pivotal movement of the lower section of the guideway. The section 20b of the guideway 20 is similarly mounted and the two lower sections 5 19b and 20b are connected together by cross bars 27 and 28. The flange 1a of the frame carries an inwardly extending rubber gasket 29 against which the window-pane may be firmly pressed to provide 10 a weathertight closure. The upper sections of the guideways may be moved laterally of the frame to press the window-pane against the gasket or to move the window-pane away from the gasket. The mechanism for moving the 15 upper section of a guideway consists of a pair of thumb screws mounted in brackets extending from the frame. Two such brackets 30 and 31 are provided for the section 19a and similar brackets 32 and 33 for the section 20a. The 20 brackets 30, 32 and 33 and the arrangement thereof are identical with the bracket 31 which is channel-shape in cross section. One of flanges 31a of the bracket is secured by rivets 34 to the frame 1; the web 31b of the bracket extends perpendicular to the frame 1 and a flange 31c extends parallel to the frame 1 so that the guideway is received between the flanges 31a and 31c and abuts against the web 31b. In an internally 25 threaded opening through the flange 31c there is a thumb screw 35 having a handle 36 on one end and an enlarged round head 37 formed on the opposite end. A grooved plate 38 is secured to the side of the guideway and forms a pocket with the guideway which receives the head 37 of the thumb screw, a constricted slot formed in the plate 38 receiving the shank of the thumb screw. The guideway is thus secured to the thumb screw against relative movement lateral to the frame. However, the thumb screw and 30 guideway may be disconnected by moving the guideway longitudinally.

The guideways are thus removable and are so removed when it is desired to remove the window-pane. When it is desired to remove the window-pane, the thumb screws in the brackets 30, 31, 32 and 33 are turned to move the guideways and the window-pane away from the gasket 29. The 35 studs 21 and 23 are removed and the guideway sections 19a and 20a are removed by lifting them vertically. The window-pane may be disconnected from the window-pane traversing mechanism by moving the carriage 13 to its uppermost position, in which position it will be directly behind the cross bar 2 and the thumb screws 17 and 18 aligned with openings through the cross bar 2. The openings are normally closed by movable covers 39 and 40 respectively, which may be 40 swung about pivots 41 and 42 to give access to the thumb screws. With the thumb screws removed, the window-pane can be easily slipped out of the frame.

From the above description of the embodiment of the invention illustrated in the drawings, it 45 will be apparent that there is provided a sturdy window construction in which the window-pane can be readily and easily removed without the aid of tools. This is an important advantage in windows of this type.

50 It is obvious that various changes may be made by those skilled in the art in the details of the embodiment described above within the principle and scope of my invention as expressed in the appended claims.

75 I claim:

1. A unitary ship's window of the type described comprising a frame having a window opening therethrough, a frameless window-pane mounted for movement longitudinally of the window frame for opening and closing the opening therethrough, and channel-shaped guideways extending longitudinally of the window frame and embracing a side edge of the window-pane, each guideway including separated upper and lower sections, means securing the lower section of each guideway to the frame with limited pivotal and lateral movement with respect thereto, and readily removable means securing the upper section of each guideway to the frame. 5 10

2. A unitary ship's window of the type described comprising a frame having a window opening therethrough, a frameless window-pane mounted for movement longitudinally of the window frame for opening and closing the opening therethrough, and channel-shaped guideways extending longitudinally of the window frame and embracing a side edge of the window-pane, each guideway including separated upper and lower sections, means securing the lower section of each guideway to the frame with limited pivotal and lateral movement with respect thereto, and a thumb-screw securing the upper section of each guideway to the frame. 15 20 25

3. A unitary ship's window of the type described comprising a frame having a window opening therethrough, a frameless window-pane mounted for movement longitudinally of the window frame for opening and closing the opening therethrough, and channel-shaped guideways extending longitudinally of the window frame and embracing a side edge of the window-pane, each guideway including separated upper and lower sections, means securing the lower section of each guideway to the frame with limited pivotal and lateral movement with respect thereto, and a thumb-screw securing the upper section of each guideway to the frame, the upper section of each guideway being slidable on the thumb screw laterally of the frame. 30 35 40

4. A unitary ship's window of the type described comprising a frame having a window opening therethrough, a frameless window-pane mounted for movement longitudinally of the window frame for opening and closing the opening therethrough, and channel-shaped guideways extending longitudinally of the window frame and embracing a side edge of the window-pane, each guideway including separated upper and lower sections, means securing the lower section of each guideway to the frame with limited pivotal and lateral movement with respect thereto, and a thumb-screw securing the upper section of each guideway to the frame, the upper section of each guideway being slidable on the thumb-screw laterally of the frame, and means for moving the guideways laterally of the frame. 45 50 55 60

5. In a ship's window of the type described, a window frame having a window opening therethrough, a frameless window-pane mounted for movement longitudinally of the window frame, traversing means for the window-pane including a movably mounted carriage having tongue-receiving grooves therein, a clamp secured to the lower end of the window-pane, tongues extending from said clamp into the tongue-receiving grooves in the carriage, and thumb-screws for securing the tongues of the clamp in the tongue-receiving grooves in the carriage. 65 70 75
